UNITED STATES PATENT OFFICE.

LEWIS J. KNIEL, OF DETROIT, MICHIGAN.

LOCKING DEVICE FOR INTERNAL-COMBUSTION ENGINES.

1,200,369.

Specification of Letters Patent.

Patented Oct. 3, 1916.

Application filed March 29, 1916. Serial No. 57,575.

To all whom it may concern:

Be it known that I, LEWIS J. KNIEL, a citizen of the United States, residing at 305 Cass avenue, Detroit, county of Wayne, and State of Michigan, have invented certain new and useful Improvements in Locking Devices for Internal-Combustion Engines, of which the following is a specification.

This invention relates to locking devices for internal-combustion engines, and is particularly designed to provide simple and effective means for disengaging certain operating parts of an engine and locking them in an inoperative position by suitable locking means, which locking means can be manipulated to restore the disengaged parts to operative position only by a person who carries the necessary key or knows the combination for releasing the locking elements employed.

My improved locking device differs materially from ordinary automobile locks in that it locks the engine itself, and not some part of the transmission mechanism, feed mechanism, etc., and while especially useful as a lock to prevent the theft of automobiles, motorcycles, etc., it is also useful to safeguard motor boats, stationary engines, etc., preventing all unwarranted operation of the engines.

This invention also provides an effective and safe locking device without in any way affecting the adjustment of the engine valves, the timing of the spark mechanism, clutches, gears, brakes, etc., but allows all adjustments to remain in any desired position while the engine is locked. Furthermore, when used with an automobile engine, my locking device allows the vehicle to be pushed or pulled (by power other than its engine) from one position to another without damaging the engine, such free movement of the vehicle being very desirable in removing the car out of danger in case of fire or accident, and permitting ready change of position in the garage or in the street.

The locking means employed in my device may be of any desired form, but I preferably employ, and herein illustrate, a permutation lock substantially the same as that shown in my prior Patent, No. 1,108,995, issued September 1, 1914. My improved locking device is along the same line as that shown in my prior patent, but is distinguished therefrom in many practical fea-

tures, the improved device having fewer parts, and such parts easily and inexpensively formed and machined, requires no apertures to be made in the gears or shafts of the engine, is more easily assembled, and is readily adaptable to engines of various sizes, types, and designs.

The essential parts of my present locking device consist of an inner rotatable member affixed to an engine shaft, an outer rotatable member affixed to an engine gear ordinarily driven by said shaft, a shiftable connecting device between the inner and outer members for driving one from the other, and lockable means for holding said connecting device out of driving relation to prevent the rotation of one of the rotatable members when desired. In the embodiment herein illustrated, I have employed an inner sleeve secured to the crank shaft of an engine, and an outer encircling sleeve secured to a gear ordinarily driven by the crank shaft, a diametrically-disposed connecting device movable through slots in both of said sleeves, and permutation locking means arranged to hold the connecting device out of engagement with the outer sleeve so that the rotation of the inner sleeve will not impart rotation to the outer sleeve.

While many other forms and arrangements of my locking device could be constructed, I illustrate and describe this preferred embodiment as an exemplification of the invention displaying its features of simplicity, effectiveness, inexpensiveness of manufacture, and ease of assembling and operation.

Reference is to be had to the accompanying drawings, wherein similar figures designate similar parts throughout the several views, and wherein—

Figure 1 is a longitudinal sectional view of my improved locking device in operative position, taken substantially on the line 3—3 of Fig. 3; Fig. 2 is a view similar to Fig. 1, but showing the parts in an inoperative position; Fig. 3 is a detail view of the inner and outer sleeves with the permutation lock removed; Fig. 4 is a detail view of the inner sleeve; and Fig. 5 is a detail elevation of one of the permutation locking means.

In the drawings, the numeral 5 designates a shaft of an internal-combustion engine and which may be the crank shaft, cam shaft, timing shaft, etc. The locking device

has been found to be particularly useful, however, when attached to the crank shaft of the engine, and is herein shown as connected thereto.

5 6 designates a gear of the engine ordinarily driven by the engine shaft, and is preferably the master gear of the engine—*i. e.*, the gear carried by the crank shaft which intermeshes with and actuates the gears 10 which control the opening and closing of the inlet and outlet valves, the timing of the spark mechanism, etc. In the assembling of my improved device, the master gear is disconnected from its former engagement 15 with the crank shaft, and is then connected to one element of my locking device, while the crank shaft is connected to another element thereof, the master gear being loose upon the crank shaft except at such times 20 as connection is made from the shaft to the gear through my locking device. When the master gear is loose upon the shaft the crank shaft may be rotated by other forces than the engine, as by a starting device or 25 through the transmission mechanism when the vehicle is moved from place to place without turning this master gear to open and close the engine valves, etc., and accordingly the engine will not operate.

30 My locking device as herein shown consists of an inner sleeve 7 suitably connected to the crank shaft 5, an intermediate member 8 being herein employed, which member is directly connected with both the crank 35 shaft and the inner sleeve. The outer sleeve 9 encircles the inner sleeve and is securely connected by any suitable means with the master gear 6, which loosely encircles the crank shaft 5. The inner sleeve 7 is formed 40 with a slot 10 (see Fig. 4) and the outer sleeve is formed with a longer slot 11, and in the assembling of the device the slots 10 and 11 are radially alined to receive the head of the reciprocable connecting member 12, which is formed with a suitable body portion extending into the guide slot 13 formed in the inner sleeve opposite the slot 10. A spring 14 encircling the body portion normally presses the head of the connecting 45 50 device outwardly so as to enter the slot 11 of the outer sleeve 9 for driving said sleeve. As herein shown, the head of the connecting device 12 is formed with an inclined rear portion adapted to contact with the inclined forward face of a slidable key 15 arranged 55 in the slot 11 of the outer sleeve and guided in its sliding movements by the walls of said slot. The slidable key 15 extends radially outward beyond the periphery of the 60 sleeve 9, and is engaged at its rear face by a portion of a short sleeve 16 slidably mounted on the outer sleeve 9 and carrying the permutation tumbler locking rings 17. Each 65 of the permutation tumbler locking rings 17 is formed with an internal annular channel 18 and the walls of this channel are notched or cut away at intervals, as at 19, (Fig. 5), the notches being so disposed that when alined the rings may be slid over the toothed locking plates 20. One or more of said 70 toothed plates 20 may be employed, as desired, the notches and plates being correspondingly spaced, and the notches being but slightly wider than the toothed plates so that only when the notches are properly 75 alined with the toothed plates can the permutation tumbler lock and the sleeve 16 be slid thereover. The channels 18 are of slightly greater width than each tooth or lug of the plates 20 so that when a notched 80 ring has been slid over a tooth or lug, the ring may be turned to throw the notch and tooth out of alinement, whereupon the ring cannot be slid in either direction along the sleeve until the notch again is in proper 85 alinement with the tooth. The periphery of each permutation tumbler locking ring is calibrated, as shown in Fig. 5, while the adjacent surfaces of the sleeves 16 are also calibrated, and it will be apparent that by 90 judicial placing of the notches in the rings relatively to the numbers upon the peripheries, any desired combination of numbers can be arranged, which must always be brought into alinement on the peripheries 95 of the rings at one particular point to allow the sliding of all the rings and the sleeve 16 carrying these rings along the outer sleeve 9. A cap plate 21 is preferably internally 100 threaded to the inner sleeve 7, and carries a flange 22 extending slightly beyond the periphery of the outer sleeve 9 so as to limit the sliding movement of the sleeve 16 in one direction, sliding movement in the other direction being limited by the contact of the 105 sleeve 16 with the forward edge of the locking plate 20.

During the sliding movement of the sleeve 16 from the position shown in Fig. 1 toward the position shown in Fig. 2, the key 15 will 110 be slid within the elongated slot 11 and the inclined face thereof will ride upon the inclined portion of the connecting member 12, forcing said connecting member inwardly 115 against the tension of the spring 14 to the position shown in Fig. 2, and forcing said connecting member out of engagement with the walls of the slot 11 of the sleeve 9. As the sleeve 16 is again slid toward the position shown in Fig. 1, the spring 14 will 120 press the head of the connecting member 12 outwardly into its free position in the slot 11.

From the above it will be apparent that with the locking device arranged on the crank shaft of an engine, the engine may be operated as long as desired, the locking device in no way interfering with the ordinary operation of the engine, since the master gear 6 is driven from the crank shaft 5 130

- through the intervention of the locked sleeves 7 and 9. When, however, it is desired to lock the engine against operation, the numbers upon the peripheries of the 5 permutation tumbler locking rings must be rotated to the position where all the notches of the several rings are in proper alinement with the toothed plates 20, and the sleeve 16 slid along the outer flange 9 so that the 10 slide key 15 will force the radially-disposed connecting device 12 inwardly out of contact with the outer sleeve 9. The permutation tumbler locking rings are then rotated to move the notches out of alinement, 15 and the engine is securely locked in an inoperative position, there being no longer any connected means between the master gear and crank shaft whereby the operation of the engine valves, the timing mechanism, 20 etc., may be controlled. To restore the engine to operative position, the permutation tumbler locking means are again rotated to bring the several notches and toothed plates into alinement, and the sleeve 16 moved into 25 its original position, the spring 14 thereupon pressing the radial connecting device 12 outwardly into engagement with the walls of the slot 11 in the outer sleeve 9 so as to permit the rotation of the outer sleeve from 30 the inner sleeve so that the master gear may again be driven from the crank shaft. A further rotation of the permutation tumbler locking rings will then lock the engine in operative position. A dial or other suitable mark may be secured to a part of the 35 engine adjacent the peripheries of the locking ring so that the location of the notches thereon may be readily referred to a fixed point.
- 40 While the permutation lock illustrated herein is well adapted for the purpose for which it is intended, it is to be understood that other forms of locks may be employed as desired, and that various changes may be 45 made in the details and arrangements of my improved locking device within the scope of the appended claims.
- Having described my invention, I claim:
1. In a locking device for engines, the combination with a rotatable shaft of the engine and a gear thereof loosely mounted on the shaft, of a pair of rotatable elements secured respectively to said shaft and gear, 5 shiftable connecting means movable into and out of position for connecting said rotatable elements for simultaneous rotation, and means for locking the connecting means in its inoperative position, said locking means comprising a series of permutation tumbler locking rings slidably mounted adjacent said rotatable elements.
  2. In a locking device for engines, the combination with a rotatable shaft of the engine and a gear thereof loosely mounted on the shaft, of a pair of rotatable sleeves
- secured respectively to said shaft and gear, shiftable connecting means movable into and out of position for connecting said rotatable sleeves for simultaneous rotation, and means for locking the connecting means in its inoperative position. 70
3. In a locking device for engines, the combination with a rotatable shaft of the engine and a gear thereof loosely mounted on the shaft, of a pair of rotatable sleeves 75 secured respectively to said shaft and gear, shiftable connecting means movable into and out of position for connecting said rotatable sleeves for simultaneous rotation, and means for locking the connecting means 80 in its inoperative position, said locking means comprising a permutation tumbler lock.
  4. In a locking device for engines, the combination with a rotatable shaft of the 85 engine and a gear thereof loosely mounted on the shaft, of a pair of rotatable sleeves secured respectively to said shaft and gear, shiftable connecting means movable into and out of position for connecting said rotatable sleeves for simultaneous rotation, and means for locking the connecting means in both operative and inoperative positions, 90 said locking means comprising a series of permutation tumbler locking rings slidably 95 mounted adjacent said rotatable sleeves.
  5. In a locking device for engines, the combination with a rotatable shaft of the engine and a gear thereof loosely mounted on the shaft, a rotatable member secured to 100 said shaft, a second rotatable member secured to said gear and surrounding the first-mentioned member, a shiftable connecting device carried by one of said members and movable into and out of contact with the 105 other of said members, and means for locking said connecting device in its operative and inoperative positions.
  6. In a locking device for engines, the combination with a rotatable shaft of the 110 engine and a gear thereof loosely mounted on the shaft, of a slotted rotatable member secured to said shaft, a sleeve member secured to said gear and surrounding the first-mentioned member, said sleeve member 115 being provided with a slot adapted to align with the slot in the first-mentioned member, a 120 slidable connecting device positioned in the slot of the first-mentioned device and movable into and out of the slot in the sleeve member, and means for locking said connecting device when out of contact with said sleeve member.
  7. In a locking device for engines, the combination with a rotatable shaft of the 125 engine and a gear thereof loosely mounted on the shaft, of a slotted rotatable member secured to said shaft, a sleeve member secured to said gear and surrounding the first-mentioned member, said sleeve member 130

- being provided with a slot adapted to aline with the slot in the first-mentioned member, a slidable connecting device positioned in the slot of the first-mentioned device and 5 movable into and out of the slot in the sleeve member, and means for locking said connecting device when out of contact with said sleeve member, said locking means comprising a permutation tumbler lock.
- 10 8. In a locking device for engines, the combination with a rotatable shaft of the engine and a gear thereof loosely mounted on the shaft, of a slotted rotatable member secured to said shaft, a sleeve member secured to said gear and surrounding the first-mentioned member, said sleeve member being provided with a slot adapted to aline 15 with the slot in the first-mentioned mem-

ber, a slidable connecting device positioned in the slot of the first-mentioned device and 20 movable into and out of the slot in the sleeve member, said connecting device comprising a reciprocating member having a head portion provided with an inclined face, means for normally pressing said member 25 into engagement with said sleeve member, a key member having an inclined face slideable in the slot in said sleeve member, and locking means including a slidable sleeve engaging said key member and a series of permutation tumbler locking rings.

LEWIS J. KNIEL.
